UNITED STATES PATENT OFFICE

ALBERT WILSON, OF CHICAGO, ILLINOIS

TYPE-COMPOSITION FRAME

Application filed December 19, 1925. Serial No. 76,354.

My invention relates to type-composition frames, designed for use by printers to maintain type-compositions in order, and the invention has for its main object the provision 5 of an improved device of this character which will embody certain desired features of simplicity, efficiency and convenience, and which will be economical in manufacture.

Another object of my invention is to provide a novel frame which can be used in place 10 of the pliable string ordinarily employed by printers in tying up page type-composition and which is so constructed and arranged that it may be applied to the page type-composition and removed therefrom as well, in 15 much less time and with greater ease than the conventional string may be applied or removed.

A still further object is to provide a novel 20 frame capable not only of effecting a great saving in time and labor, but capable also of securely maintaining page type-composition in order against the disruption or separation of its parts.

Still another object of my invention is to 25 provide a frame having means thereon by which vertically to withdraw it from the type-composition where a number of page type compositions are being arranged on the 30 imposing stone.

Other objects will appear hereinafter.

The invention consists in the combinations 35 and arrangements of parts hereinafter described and claimed.

The invention will be best understood by reference to the accompanying drawings forming a part of this specification, and in which,

Fig. 1 represents a fragmentary view showing 40 in top plan an arrangement of my improved frames for holding type-compositions;

Fig. 2 is an elevational view showing the 45 separable hinge;

Fig. 3 is a cross-section taken on the line 3—3 of Fig. 2;

Fig. 4 represents a detailed plan view of 50 one of the hinges associated with the back strip of the frame;

Fig. 5 represents an end elevational view, 55 partly in section, showing a form of device that may be employed for withdrawing the frame from the type-composition;

Fig. 6 is a cross-section taken on the line 6—6 of Fig. 5;

Fig. 7 represents a top plan view of the 60 parts shown in Fig. 5; and

Fig. 8 is a sectional elevation taken substantially on the line 8—8 of Fig. 5. 65

The preferred form of construction, as illustrated in the accompanying drawings, comprises a framing for walling in and binding together page type-compositions so as to 70 securely maintain the type-compositions in proper order and arrangement against the disruption or separation of their parts. Preferably and as shown, the framing consists of a pair of opposed strips 9, 9', which I may designate as end strips, and a pair of opposed 75 strips 10, 11, which I may more particularly refer to as front and back strips, respectively, for the purpose of differentiation. These strips are vertically-positioned so as to provide a wall for encompassing the type-composition and are connected by outside hinges, 80 of which hinge 12 is a separable hinge, herein shown as comprising a hinge knuckle 13 arranged on the front extremity of the end strip 9' and of a co-operating hinge knuckle 14 arranged on the adjacent end of the front strip 10 and provided with a hinge pin 15 enterable in the hinge knuckle 13 from the top end thereof. By means of this arrangement, 85 the front strip 10 may be readily coupled to or uncoupled from the end strip 9' when the framing is applied to a page type-composition as 16, fractionally shown.

The hinge connection between the front strip 10 and the end strip 9 preferably con- 90

sists of what may be termed a loose hinge 17, the same being adapted not only to permit the said front and end strips 10 and 9 to swing relatively to each other upon the hinge pin 18 but also to permit said front end 10 to have relative vertical movement with respect to the end strip 9 so that the hinge pin 15 may be readily engaged with and disengaged from the hinge knuckle 13. To this end, the hinge pin 18 is preferably secured to the hinge knuckles 19 of the front strip 10 and is loosely fitted in the hinge knuckle 20 of the end strip 9, which hinge knuckle 20 is arranged between the hinge knuckles 19 as clearly depicted in Fig. 2.

The strips composing the framing are preferably made of spring material adapted to yield so as to permit the opening movements of the rear hinges 22, as best illustrated in Fig. 4. When, under this arrangement, the hinge connected strips are arranged about a page type-composition, they may be readily drawn together and tightened on the page type-composition as a wall extending thereabout, by engaging the hinge pin 15 with the hinge knuckle 13. By making the hinges on the outside, the inside faces of these strips are free to hug the corners of the type-composition. When there is space around the page type-composition for the spreading of the hinge connected strips, the framing may be removed by withdrawing the hinge pin 15 from the hinge knuckle 13 and thereupon spreading one or more of the strips so as to admit of the removal of the framing without disturbing the type-composition. To enable the ready application or removal of the hinge pin 15, I preferably provide a lug 23 on the end strip 9' and another lug piece 24 on the front strip 10, so that by resting the forefinger on the lug 23 the thumb may be conveniently utilized to engage the lug 24 either for lifting up or for pushing down, the front strip 10. Where the framing is to be removed from a type-composition comprising one of a number of type-compositions arranged on an imposing stone, I provide a special device for withdrawing the framing vertically of the type-composition. For this purpose, the end strips 9 and 9' are provided with suitable hook engaging lugs 25.

As herein illustrated, the means for vertically withdrawing the framing from the type-composition comprises a lever-operated device including a plate 26 adapted to repose on the type-composition, said plate being preferably provided on its under face with a layer of felt 27 or other suitable material adapted to prevent any marring of the surface of the printing type. Rising centrally from the plate 26 is a post 28 bifurcated at its top to provide the opposing guide arms 29. Arranged between the guide arms 29 so as to have vertical sliding movement thereon is a saddle plate 30 to which are pivoted at their

lower ends a pair of links 31. The upper ends of the links 31 are operatively engaged on a pivot pin 32 operative in a slot 33 provided in the end of an operating lever 34 fulcrumed at 35 on suitable ears 36 provided for the purpose on the guide arms 29. Arranged in the extremities of the saddle plate 30 are rods 37 whereon are pivoted the upper ends of lifting arms 38 which are formed at their lower ends with hook members 39 adapted to be engaged with the hook receiving lugs 25. By this arrangement the type composition within the framing is held in order by the pressure of the plate 26 while the framing is drawn bodily vertically from the type-composition when the operating lever 34 is moved in a downward direction. Preferably and as shown, a shank 40 is secured between the upper ends of the guide arms 29, and there is superposed on said shank a head member 41 whereon the hand may be suitably rested during the withdrawing of the framing from the type-composition.

While I have illustrated and described the preferred form of construction for carrying my invention into effect, this is capable of variations and modification without departure from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A type-composition frame composed of hinge connected strips adapted to be engaged about a type-composition to provide a wall thereabout and capable of securing the parts of the composition against separation, said strips made of spring material and adapted to yield so as to facilitate the removal of the frame substantially as described.

2. A type-composition frame composed of a series of hinge connected strips made of spring material adapted to be engaged about a type-composition to provide a wall thereabout; the connected strips being adapted to yield so as to permit the opening movement of the back hinges; two of said connected strips comprising end strips; and interengaging means on the free extremities of said end strips, one of the hinges being a separable hinge comprising a hinge pin mounted upon one strip removably received in a hinge knuckle provided on the adjacent strip substantially as described.

3. A type-composition frame composed of side and end strips held together by hinges and adapted to be engaged about a type-composition to provide a wall thereabout; the back strip made of spring material and adapted to yield to permit the opening movement of the back hinges said hinges being

arranged on the outside faces of said strips; and one of the front hinges being a separable hinge, comprising a hinge pin removably received in a hinge knuckle, substantially as described.

5 4. A type-composition frame composed of strips of spring material held together by hinges to provide a wall about the type-composition; and lugs on said frame by which it is adapted to be withdrawn vertically as a rigid unit from the type-composition, substantially as described.

10 In testimony whereof I have signed my name to this specification.

15

ALBERT WILSON.
